UNITED STATES PATENT OFFICE.

BURTNELL MCINTOSH, OF BROOKLYN, NEW YORK, ASSIGNOR TO FRANK A. HALL, OF MONTCLAIR, NEW JERSEY.

CORNER-LOCK FOR BEDS OR THE LIKE.

1,265,798.

Specification of Letters Patent.

Patented May 14, 1918.

Application filed July 7, 1916. Serial No. 107,884.

To all whom it may concern:

Be it known that I, BURTNELL MCINTOSH, a citizen of the United States, residing at Brooklyn, in the county of Kings and State 5 of New York, have invented certain new and useful Improvements in Corner-Locks for Beds or the like, of which the following is a specification.

This invention relates to bed-steeds, and 10 more particularly provides an improved coupling for corner-post and side-rail.

The coupling member which constitutes the invention, preferably embodied as a single unitary casting, includes a socket for 15 receiving the side-rail end when the bed-steed is assembled. A tail-piece or plate is offset from the closed end of the socket and carries devices for interlocking with coöperant devices on a familiar coupling member 20 carried by the corner-post. A rib or side-wing is laterally offset from the socket and arranged perpendicular to the plate, for supporting the bed-spring. The various elements of the casting are so designed, pro- 25 portioned, disposed and webbed together that a casting of extreme lightness but of very great strength is provided, for coöperating in a novel manner with the other parts of the bed-steed and with the bed- 30 spring.

The invention will be most clearly understood from the following description, when taken in connection with the accompanying drawing, of which—

Figure 1 is a perspective view of the complete bed, assembled;

Fig. 2 is an enlarged detail view, illustrating the coupling in side elevation;

Fig. 3 is a view similar to Fig. 2, but 40 showing the coupling members interlocked, and disclosing a modification in that the two members are bolted together;

Fig. 4 is a section on the line 4—4 of Fig. 3; and

Fig. 5 is a perspective view of the unitary side-rail casting looking to the right of Fig. 2.

The assembled bed shown in Fig. 1 includes head and foot sections 6 and 7, side-rails 8, and a bed-spring 10 comprising head and foot angle-irons 9 and a mattress-supporting wire-structure made up of a net 11 and coil-springs 11^a connecting the net and the angle-irons.

The corner-posts 12 of the head and foot

sections are each sleeved by a casting 13, sweated on. As shown best in Figs. 2 and 4, each casting 13 consists of the main tubular portion 14 which surrounds the corner-post and a longitudinally offset plate 15. This 60 plate is formed to provide an upper recess 16, a lower recess 17 and a binding edge 18. The two recesses are arranged one vertically below the other, the binding edge being inclined downwardly and away from the corner post. This casting 13 forms a structure the general features of which are familiar in the art.

My improvement concerns itself solely with the provision of a novel device embodied also as a single casting. Such novel casting is indicated at 19 in Fig. 2 and shown in perspective in Fig. 5. Four of these castings 19, carried by the side-rails 8 as indicated in Fig. 1, are adapted to act 70 not only as companion fasteners to the four castings 13 on the corner-posts 12 and thus permit the side-rails 8 to be readily coupled and locked to the head and foot sections 6 and 7, thereby to assemble the bed, but also 75 to act as direct supports for the angle-irons 9 of the bed-spring 10.

As shown best in Figs. 2, 4 and 5, my casting 19 includes a horizontal tubular part or socket 20 for receiving an end of a side-rail 85 8. Laterally offset from the socket is a rib or transverse wing 21, and longitudinally offset from the socket is a tail-piece or plate 22. A web 23 joins the web and socket. The web 23 and the plate 22 are parallel, but in 90 staggered relation, with the web arranged above the axis of the tubular socket.

The plate 22 is recessed as indicated at 24, and thus the plate near its top is disconnected from the wing 21; but the joining of 95 the plate 22 and the wing 21 is reinforced by a lug 25 which is formed on the casting between the plate and wing at a point just above the joining of the wing to the socket 20. This lug as well as upper and lower pins 26 and 27 formed on the plate 22, are all arranged on the side of the plate 22 100 nearest the axis of the socket and hence lie opposite the web 23 overlying the socket.

The cylindrical wall of the socket 20 is 105 shaped so that the length of the roof of the socket is equal to the length of the base of the web 23, but the floor of the socket is much shorter. A lug 28 may be provided, not only to strengthen the joining of the 110

plate 22 to the socket, but also to strengthen the floor and end-wall 29 of the socket.

Before the bed is assembled, the separate parts to be interlocked to build up the bed are preferably five, namely, the bed-spring 10, the head and foot sections 6 and 7, and the two side-rails 8; each of the side-rails carrying at opposite ends two castings 19 arranged thereon as indicated in Fig. 1. Each side-rail 8 is preferably tubular and provided at each end with a notch or recess 30 which engages the lug 28 when the socket of the casting 19 within which the lug is formed receives a rail end. The four castings 19 may be permanently secured to the ends of the two side-rails.

In assembling the bed, the side-rails equipped with their castings 19 are first connected to the corner-posts 12. As each casting 19 is advanced toward its companion casting on a corner-post, the post is held fixed in substantially a vertical position, while the rail is so guided that the plate 22 supported on the rail is arranged relatively to the plate 15 supported on the post as shown in Fig. 2, and then the plate 22 is lower alongside and in contact with the plate 15 until the pins 26 and 27 enter the recesses 16 and 17 and the lug 25 binds and locks against edge 18 as shown in Fig. 3. After the side-rails 8 are thus connected to the corner-posts 12, the bed-spring 10 is arranged in place as indicated, the dependent vertical members of angle-irons 9 entering recesses 24 and the horizontal members of the angle-irons resting on the flat upper edges of wings 21.

It may be desirable to provide a special and supplemental interlocking means for the plates 15 and 22, as where the bed is to be used in a hospital, insane asylum or the like. In such a case, the two plates are transversely apertured in such a way that the apertures will register when the bed is assembled, so that a bolt may be passed through the apertures and a nut threaded on the bolt. Thus in Fig. 3 the assembled plates 15 and 22 are shown as provided with registering apertures 31, a bolt 32 extending through these apertures and being clamped tight by a nut 33 threaded on the bolt. The apertures 31 are formed as slots, in order to allow for future wear between the recesses 16 and 17 and edge 18 and their co-acting pins 26 and 27 and lug 25.

Whether or not the apertures 31 be present, it will be seen that I provide a single member, in the shape of the unitary casting 19, to be carried by a side-rail and readily locked to and unlocked from a corner-post of the bed. The casting is of light weight and great strength. When the castings 13 and 19 are interconnected, the lug 25 bears tight against the binding edge 18 to hold the parts frictionally locked against hori-

zontal displacement, and, as shown best in Fig. 4, both the plates 15 and 22 coöperate with the web 23 in strengthening the wing 21 and rigidifying the entire coupling structure. The staggered relation between plate 22 and web 23 causes the web to extend in prolongation of the plates 15 and 22 when coupled. The web 23 also coöperates with socket 20 to strengthen the wing 21 which directly supports the bed-spring angle-irons 9. The upper part of plate 22 is presented edgewise to the recess 24, to withstand the tendency of the angle irons to rock out of place when a heavy load is put on the net 10. The elongation of the socket 20 adjacent the base of the web 23 adds strength where it is most needed, and at the same time permits the socket to be shaped at its bottom and sides as illustrated to save weight and metal. It is obvious of course that other bed-springs may be used in connection with the bedstead above-described, even a bed-spring of the familiar kind having four dependent feet designed to rest on side-rails 8 at points slightly removed from the four corner-posts 12, the parts herein illustrated being so shaped that these feet will clear the sockets 20 and yet properly seat the bed-spring in place. Any type of bed-spring carrying equivalents of the vertical members 9 of angle-irons 9 at its top and bottom or at its four corners, to enter the recesses 24, is preferred, however; and is required to attain the fullest advantages of the invention. For it is clear that a light weight and easily handled bed-spring, that is, one similar to the bed-spring 10 in that rigid side-rails for the bed-spring are dispensed with, will have peculiar and valuable characteristics. In the first place, when the bed-spring 10 is once placed in position on wings 21, it may not be displaced lengthwise of the bed. As soon as a weight is placed on the spring, even the weight of a light mattress, the angle-irons are rocked sufficiently in the recesses 24 to bind their lower edges tight against the plates 22, and then the bed-spring may not be displaced laterally of the bed. Finally, such tilting of the angle-irons 9 on the upper edges of wings 21 of castings 19 will tend to jam the lugs 25 on these castings tighter against the binding edges 18 of castings 13. If necessary, the angle-irons may be bolted to the wings 21; and in any event the castings directly support the spring, and the wings all extend inwardly.

The construction selected and described to illustrate my improvement may be variously modified in the arrangement of its parts and in the substitution of elements having equivalent functions without departing from the essence of the invention. The scope of my invention will be indicated by the appended claim.

I claim:

In a corner fastener, the combination of a corner post, a plate secured to the corner post provided with vertical outstanding recessed portions and an intermediate binding edge, a side rail, a wing plate provided with a socket on its rear face to receive the side rail and a vertical outstanding plate on its front face, said vertical outstanding plate provided with projections adapted to

engage in the recessed portions of the corner post plate, and an integral transverse lug arranged at the juncture of the vertical outstanding plate and the wing plate and adapted to coöperate with the binding edge 15 on the corner post plate to frictionally lock the parts in position.

In testimony whereof I affix my signature.

BURTNETT McINTOSH.
